SADDLEBAG

William G. Davidson, Elm Grove, Wis., assignor to Harley-Davidson Motor Co., Milwaukee, Wis., a corporation of Wisconsin

Filed Aug. 5, 1963, Ser. No. 76,100

Term of patent 7 years

(Cl. D90—3)

FIG. 1 is a view in side elevation of a saddlebag embodying my design.

FIG. 2 is a plan view thereof.

FIG. 3 is a front elevational view thereof.

FIG. 4 is a rear elevational view thereof.

FIG. 5 is a view thereof in bottom plan.

FIG. 6 is a view taken in cross section on the line 6—6 of FIG. 1.

I claim:

The ornamental design for a saddlebag, as shown.
